UNITED STATES PATENT OFFICE

DARRELL C. CRAIN, OF WASHINGTON, DISTRICT OF COLUMBIA

DESIGN FOR A BADGE

Application filed December 30, 1931. Serial No. 42,299. Term of patent 7 years.

To all whom it may concern:

Be it known that I, DARRELL C. CRAIN, a citizen of the United States of America, and a resident of Washington, District of Columbia, have invented a new, original, and ornamental Design for Badges, of which the following is a specification, reference being had to the accompanying drawings, forming part

view and Fig. 2 a side view of a badge embodying my new design.

I claim:

The ornamental design for a badge, as shown.

In testimony whereof I have signed this specification.

DARRELL C. CRAIN.
